THREAD HOLDER FOR LOOMS

Oscar V. Payne, Leicester, Mass., assignor to
 Crompton & Knowles Loom Works, Worcester,
 Mass., a corporation of Massachusetts

Application October 29, 1934, Serial No. 750,404

2 Claims. (Cl. 139—257)

This invention relates to thread holders for weft replenishing looms and it is the general object of the invention to provide a device of this type so constructed as to tension evenly any one 5 of a number of threads, particularly coarse yarns.

Heretofore I have proposed a thread holder having a pair of fluted rolls between which pass the weft ends extending from a reserve magazine. The rolls are ordinarily constructed so as to tension the threads without causing unwinding at 10 the bobbin, and keep them taut so that they will be above the path of the moving lay. As shown in my Reissue Patent No. 19,100 the rolls are caused to turn by a force derived from a suspended weight which is moved by loom vibration.

When adapting a thread holder of this general type for use with coarse yarns I have found that the rolls should be comparatively large both as to diameter and length and I have also found 20 that it is desirable to have a considerable length of thread between the rolls and the guide surface over which the threads pass when moving from the magazine. It is an important object of my present invention to provide means for mounting 25 relatively large rolls at a substantial distance from the guide surface preferably in such a way that this distance can if desired be varied to meet conditions arising from differently sized yarns.

Because of the size of the rolls I deem it 30 advisable to mount them on a support independent of the loom and not vibrating with the latter. Because of this fact the previously mentioned swinging weight cannot be used to advantage, and in its place I employ a pawl and ratchet feed actuated by some moving part of the loom. As shown herein the drive is derived from the lay preferably by connections from the rocker iron which supports the picker stick, although this particular relation is not essential.

40 When heavy yarns are used there is a tendency in former thread holders for the threads to bunch together with resultant uneven tensions. It is a further object of my invention to provide a guide surface for the threads so curved as to effect a distribution of the threads so they will tend to spread out to form substantially a single sheet of threads all of which can be subjected to substantially the same tension.

With these and other objects in view which 50 will appear as the description proceeds, my invention resides in the combination and arrangement of parts hereinafter described and set forth in the claims.

In the accompanying drawings, wherein a 55 convenient embodiment of my invention is set forth,

Fig. 1 is a front elevation of one end of the loom showing my invention.

Fig. 2 is an enlarged front elevation of certain parts of Fig. 1.

Fig. 3 is an end elevation taken in the direction 5 of arrow 3, Fig. 2.

Fig. 4 is a plan view taken in the direction of arrow 4, Fig. 2.

Fig. 5 is a detailed vertical section on line 5—5 10 of Fig. 4.

Fig. 6 is a detailed plan view in the direction of arrow 6, Fig. 1, and

Fig. 7 is a diagrammatic view showing the relation between the threads from the reserve bobbins, 15 the curved surfaces of the guide, and the rolls.

Referring particularly to Fig. 1, the loom frame 10 supports a lay 11 having swords one of which is shown at 12. A rocker shaft 13 supports the lay and has suitable bearings in the loom frame. Extending from the end of the shaft is a rocker 20 iron 14 secured to the shaft 13 and rocking with the latter and the lay. The bottom shaft 15, picking arm 16, picking shoe 17, sweep arm 18 and picker stick 19 may be of usual construction. The stick is preferably pivoted as at 20 to the 25 rocker iron 14 in the usual manner.

The magazine M is attached to the loom frame and accommodates a series of bobbins B from which extend weft ends W.

The loom may be of the usual multicolor weft 30 replenishing type and will be equipped with a magazine M having reserve bobbins B with weft ends W, together with mechanism not shown for bringing about a transfer of one or another of the bobbins into the active shuttle. After a fresh 35 bobbin is inserted into the depleted shuttle it will be picked to the opposite side of the loom and the shuttle eye threading operations require that the thread end of the freshly transferred bobbin shall be held sufficiently tight to cause the weft 40 to be drawn down into the shuttle eye. Another reason for holding the weft ends taut results from the jarring and vibration incident to loom operation, causing the bobbins to turn on their axes and unwind the weft ends until they fall 45 low enough to be in the path of and become broken by the lay. The mechanism to be described hereinafter has as an important object the tightening or straightening of the weft ends so that they will be at all times taut enough for 50 shuttle threading and above the lay, substantially as shown in Fig. 1.

In carrying my invention into effect I provide a thread holder designated generally at T preferably supported independently of the loom and 55

adjacent the magazine end thereof, as set forth in Fig. 1. The holder comprises a base 30 and an upright pipe 31 held therein by a screw 32. The top of the pipe has secured thereto a thread 5 guide 33 which may be formed substantially as shown in Figs. 2 and 3 with a surface C that is convex in a plane substantially parallel to the lay as shown in Fig. 2 and concave with respect to a plane transverse of the lay. Vertical walls 10 or cheek plates 34 may be secured to the sides of the holder to keep the threads from slipping off the curved surface. The guide has a depending shank 35 through which extends a holding screw 36 and by means of which the guide is 15 held to the top of the pipe.

The thread feeding mechanism comprises a casing 40 in which are mounted for rotation a pair of fluted rolls 41 and 42, respectively, each having vanes or teeth 43 so moving that each 20 set of vanes intersects the path of movement of the other set to cause a thread lying between the two rolls to be deformed. Roll 41 is secured to a stud 45 rotating in a fixed bearing 46 of the casing, while the other roll rotates around a 25 second stud 47 fixed to the casing and the position of which is adjustable relatively to the axis of roll 41. The particular mode of mounting the rolls may be substantially as set forth in my prior Patent No. 1,979,765 to which reference may be 30 had for a more complete understanding of the mounting. Horizontal slot 52 in the casing permits the stud 47 to assume any one of a plurality of positions relatively to the other stud. The casing 40 may have an overhanging ledge 48 as 35 set forth in the last named patent to keep the weft ends from being caught between the casing and the adjacent ends of the fluted rolls. The casing is held in vertically adjusted position on the pipe by means of a set screw 49.

40 In order to impart motion to the rolls I secure to stud 45 a ratchet wheel 60 and arrange the same in the path of a vertically reciprocating pawl rod 61. The latter has a pointed head 62 to coact with the teeth of the ratchet wheel and 45 a light spring 63 interposed between the rod and a fixed part of the casing holds the head 62 against the ratchet.

In order to reciprocate the rod 61 I provide 50 an oscillatable rod 65 shown particularly in Figs. 1 and 6 having on the inner end thereof a head 66 which is held to the rocker iron 14 by screws 67. The rod extends outwardly and may be offset as at 68 so that the outer end 69 thereof is substantially in alignment with the axis of 55 shaft 13. The base 30 has a web 70 through which the end 69 of the rod passes so that it will be guided and held against undue vibration. I find that it is not necessary to provide a close 60 running fit between the rod and the web 70.

60 A rocking arm 75 is held in angular adjustment on the rod by means of a set screw 76 and has the outer end thereof slotted as at 77 to receive a stud 78 locatable at various distances from the shaft end 69. The lower end of the pawl rod 61 is 65 pivotally supported on the stud 78.

During normal loom operation the shaft 13 will 70 rock back and forth in its bearings and will cause an oscillation of the rocker iron 14. This in turn causes movement of the rod 65 and causes the outer end 69 thereof to have an oscillating movement similar to that of the rocker shaft. The arm 75 is therefore raised and lowered alternately, moving up as set forth herein when the lay moves forwardly, although I do not deem this 75 an essential relation. When the arm 75 rises the

head 62 of the rod 61 will give the ratchet wheel and therefore fluted roll 41 a partial rotation in a counter-clockwise direction as viewed in Fig. 3. By means of a force transmitted through the 5 yarns the other fluted roll will be caused to rotate in the opposite direction, thereby causing a deformation in the yarns which tensions and holds them taut. As the lay moves backwardly the pawl will have an idle or non-working down stroke and will slide over the ratchet without 10 causing retrograde movement thereof.

Another feature of the invention relates to the spreading of the several weft ends into sheet 15 form so that the tension on the threads might be uniform. This result I accomplish by providing the guide with a surface having a compound curve as already described. I find in practice that the weft ends which are drawn from the magazine distribute themselves over the curved surface C without objectionable overlapping and 20 that after leaving this surface they spread out somewhat fan-shaped as they approach the rolls 41 and 42.

The behaviour of the threads is similar to that 25 shown in Fig. 7, where the vertical lines 80 and 81 represent two slots in the magazine from which the weft ends issue. The threads from each slot extend down in a sheet as shown, the upper threads tending to move toward the center 30 of the curve C, and the lower threads toward the outer edges thereof. After leaving the curved 35 surface C the threads spread out as shown in the lower part of Fig. 7, and avoid bunching or crowding. In this way the several threads are subjected to more or less the same tension and the feed of the pawl and spacing of the rolls can 40 be set to give a minimum but sufficient drawing action on the weft ends to keep them above the lay and cause proper threading of the shuttle eye.

In Fig. 7 the areas covered by shade lines 45 represent the sheets of weft threads or ends and the lines extending across these areas are for the purpose of indicating the twist in the sheets as they pass toward and beyond the guide surface.

From the foregoing it will be seen that I have 50 provided a form of thread holder adaptable for the use of coarse yarns and so constructed that the threads spread out in a sheet of more or less uniform thickness to prevent lapping or crowding. By using an independent mounting for the 55 thread guide and rolls I am able to make these devices in large enough proportions to accommodate the coarser threads for which they are more particularly designed. While the thread guide and rolls are mounted on a support independent of the loom yet I do not wish necessarily to be limited to this mode of support. It will also be seen that the thread guide and rolls are so mounted that relative adjustment of the distance 60 between them can be effected and also each of these devices is angularly movable about the pipe 31. The result of this relation permits a 65 change in the direction of delivering the threads from the guide toward the rolls. Furthermore, I have provided a simple means for actuating the rolls by a connection of the rocker iron of the lay. The control of the threads is considerably 70 facilitated by having the guide surface curved in such a way that it is concave in a cross section transverse of the weft ends and convex in a cross section parallel to the weft ends.

Having thus described my invention it will be seen that changes and modifications may be made therein by those skilled in the art without 75

departing from the spirit and scope of the invention and I do not wish to be limited to the details herein disclosed, but what I claim is:

1. In a weft replenishing loom, a magazine from which extend weft ends in two spaced sheets, a pair of rotatable tensioning rolls having teeth moving in paths which intersect along a line below the magazine and pointed in the general direction of the magazine, and a thread 10 guide located between the magazine and rolls to produce a bend in the weft ends, said guide having an upwardly facing curved thread engaging surface convex with respect to the line along which the weft ends lie and concave upwardly in 15 a direction transverse to the line along which the weft ends lie, the weft ends of one sheet extending along the adjacent part of the concave surface and the weft ends of the other sheet extending along another part of the concave surface adjacent to said other sheet, the weft ends passing down uninterruptedly from the guide surface to 20 the rolls and being spread out along said line of the intersecting paths.

2. In a weft replenishing loom, a magazine to

hold a pair of stacks of reserve bobbins, the weft ends of the stacks leading from the magazine in spaced sheets, a pair of rotatable weft tensioning rolls having teeth which travel in paths that intersect along a line substantially parallel to the axes of the bobbins in the magazine, and a weft end guide interposed between the magazine and rolls, said guide having a weft end engaging surface which is concave upwardly along a section taken transverse of the line along which the said paths intersect and said surface being convex along a section substantially parallel to the line along which the said paths intersect, the central part of the guide surface measured transversely of the weft ends being lower than the outer parts 10 thereof, the weft ends passing down uninterruptedly from the engaging surface to the rolls, the weft ends from each stack of bobbins being spread out over that part of the engaging surface on the side of the said central part adjacent the stack, and the weft ends extending in a sheet toward said line along which the said paths intersect. 15

OSCAR V. PAYNE.
